UNITED STATES PATENT OFFICE

160,247

SHOE OR SIMILAR ARTICLE

Walter Braun, Los Angeles, Calif.

Application May 27, 1949, Serial No. 2,907

Term of patent 7 years

(CL. D7—7)

To all whom it may concern:

Be it known that I, Walter Braun, a citizen of the United States, residing in Los Angeles, in the county of Los Angeles, State of California, have invented a new, original, and ornamental Design for a Shoe or Similar Article, of which the following is a specification, reference being had to the accompanying drawing, forming a part thereof.

The essential features of my design include the symmetrical curved delineation of the upper edge of the shoe, from the upper part of the tongue down the curved line around the notch between the tongue and the waist; in combination with the special configuration of the heel portion of the shoe as shown most clearly in Figure 2.

I claim:

The ornamental design for a shoe or similar article, as shown and described.

WALTER BRAUN.
